(57) **CLAIM**

The ornamental design for a connector for television receiver, as shown and described.

DESCRIPTION

FIG. 1 is a front perspective view of a connector for television receiver showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion 9 in FIG. 1;

FIG. 10 is an enlarged view of the encircled portion 10 in FIG. 2;

FIG. 11 is an enlarged view of the encircled portion 11 in FIG. 4;

FIG. 12 is an enlarged view of the encircled portion 12 in FIG. 5;

FIG. 13 is another perspective view thereof in which a television receiver is shown in broken lines to illustrate example environment;

FIG. 14 is an enlarged view of the encircled portion 14 in FIG. 13;

FIG. 15 is an enlarged view of the encircled portion 15 in FIG. 13;

FIG. 16 is an enlarged view of the encircled portion 16 in FIG. 13; and,

FIG. 17 is an enlarged view of the encircled portion 17 in FIG. 13.

(Continued)

The broken lines in the figures depict portions of the connector for television receiver which form no part of the claimed design.

The broken lines in FIGS. 13-17 illustrating the television receiver are for environmental purposes only and form no part of the claimed design.

The dot-dash broken lines encircling portions of the claimed design that are illustrated in enlargements form no part of the claimed design.
